PUMP

Floyd E. Carlson, Rockford, Ill., assignor to Sundstrand Machine Tool Co., a corporation of Illinois

Application May 12, 1950, Serial No. 161,539

7 Claims. (Cl. 103—158)

1

This invention relates to a pump, and more particularly to a pump having improved means for providing a seal between the inlet and outlet ports thereof.

The general object of this invention is to provide an improved pump.

Another object of this invention is to provide a pump having a non-rotatably mounted cylinder block which is bodily movable in a generally circular path within a cylindrical chamber with an end wall having inlet and outlet openings, said block having an end face engaging said end wall and at least one cylinder port opening into said end face, and means for exerting variable pressure to force the end face of the block against the end wall of the chamber.

Another object is to provide a pump of this character in which said variable pressure increases as the speed of movement of the block increases.

Another object is to provide a pump of this character in which the means for exerting variable pressure comprise a flyball governor device on the drive shaft of the pump and a thrust bearing between the governor and the cylinder block, said governor having a cam surface engaging a follower to increase the pressure of said bearing as the speed of rotation of the drive shaft increases.

Another object is to provide a pump in which the drive means may be started and brought up to substantially full speed before the full load is applied to reduce torque during starting and acceleration of the drive means and in which the load is removed as the drive means decelerates.

Another object is to provide a pump of this character in which the means for exerting variable pressure comprise a spider secured to the drive shaft, a pair of weights pivotally mounted on the spider and movable away from the drive shaft as a function of the speed of rotation of said shaft, and a thrust bearing between the weights and the cylinder block, said weights each having a cam surface engaging a follower to increase the pressure as the speed of rotation of the shaft increases.

Other objects will become readily apparent from the following detailed description taken in connection with the accompanying drawings in which:

Fig. 1 is a longitudinal section through a pump constructed in accordance with the invention, taken along the line 1—1 of Fig. 2;

Fig. 2 is a transverse section through the 55 will hereafter be described. Pistons 29a, 29b and

2

center of the cylinder block, looking to the right in Fig. 1, underlying parts being shown in broken lines; and

Fig. 3 is a fragmentary transverse section 5 taken along the lines 3—3 of Fig. 1.

While there is shown in the drawing and hereinafter described in detail a preferred form of the invention, it is to be understood that the invention is not limited to the particular form and 10 arrangement shown. It is contemplated that various changes may be made by those skilled in the art without departing from the spirit and scope of the appended claims.

Referring now to the drawings, the pump 15 comprises a casing designated generally at 10 and including a cup-shaped body having side walls 11, a base 12 and a cover member 13 which may be secured on the cup-shaped body by a plurality of bolts 14.

20 Within the casing 10 is a chamber 15 having a cylindrical wall 15a and having an end wall 15b formed by the inner surface of the cover member 13. This end wall has an inner recess 16 which communicates by means of a passage 17 with an outlet port 18 in the cover of the casing. An annular rib 19 having an inner surface 19a which forms part of said end wall 15b of the chamber 15, separates the inner recess 16 from a concentric annular outer recess 20. This outer recess communicates by means of a passage 21 with an inlet port 22 in the cover member 13.

A cylindrical cylinder block 25 is non-rotatably mounted within the chamber 15, the cylinder block having a smaller diameter than said chamber. The cylinder block has one end face 25a engaging the end wall 15b so that the surface 19a of the annular rib 19 may, by engagement with the end face 25a, form a seal between the recesses 16 and 20. The cylinder block 25 has a central well 26 in its other end face which does not extend through the block, as shown in Fig. 1. The cylinder block 25 has equally spaced around its periphery a plurality of cylinders 27a, 27b and 27c, which are preferably angular to radii of the block in order to increase the length of the cylinders. Each cylinder has near its inner end a port 28a, 28b and 28c respectively, which ports open into the end face 25a of the cylinder block. It is not necessary that the ports open directly into the face of the cylinder block, but the ports may extend through channels defining an arc and opening into said end face 25a in positions to give properly timed valve action, as

29c are mounted one in each cylinder for reciprocation therein. Each piston has a portion extending out of the cylinder and engaging the cylindrical wall 15a of the chamber 15, as shown in Fig. 2. Springs 30a, 30b and 30c are provided to urge the pistons outwardly, although these springs are not necessary if the pump intake is under pressure.

A drive shaft 31 is rotatably mounted in sleeve bearings 32 and 33 in the casing 10, and the inner end of the shaft has an eccentric projection 31a forming a crank which fits movably in the well 26 of the cylinder block 25, a bushing 34 providing a rotatable mounting for the crank in the well. A flexible sleeve 35 connects the block 25 with the end wall 12 of the casing. This sleeve is connected at one end to the cylinder block by clamping bolts 36, a clamping ring 37 and a gasket 38. The other end of the sleeve is connected to the casing by means of clamping bolts 39 which extend through the casing base 12, a clamping ring 40, and a gasket 41. The flexible sleeve 35 surrounds the shaft 31 and provides a non-rotatable seal between the cylinder ports and the shaft, and consequently no rotary seal is required for the shaft 31. A drain 42 is provided between the chamber 15 and the inlet 22.

A spider 45 is pinned to the drive shaft 31 and a pair of oppositely disposed weights 46a and 46b are pivotally mounted on the spider, these weights each having a cam surface 46a' and 46b' for engagement with an annular follower 47 forming part of a thrust bearing having an annular member 48 secured to the cylinder block 25. In the space between the members 47 and 48 is a ball retainer 49 carrying a plurality of anti-friction balls 50.

In the operation of the pump, the drive shaft is rotated and the eccentric crank 31a causes the cylinder block 25 to move bodily in a generally circular path in the chamber 15. The block is held against rotation by the sleeve 35, although the flexibility of the sleeve permits arcuate movement of the block about its axis when necessary. As the block moves bodily within the chamber 15, the pistons 29 are reciprocated successively through compression and suction strokes and the respective ports 28 are moved across the surface 19a of the annular rib 19 alternately into communication with the recesses 16 and 20. As pointed out above, the positions at which the respective cylinder ports 28 open into the end face 25a provides proper valving action in correctly timed relationship with the reciprocal movement of the pistons.

Obviously, in order to create a pumping action the recesses 16 and 20 must be sealed one from the other, for if no seal exists no pressure in excess of the inlet pressure can be developed in the outlet, but the fluid being pumped will merely flow back to the inlet on the compression stroke of each piston. As the drive shaft 31 is rotated, the weights 46 act as a flyball governor device and move outwardly away from the shaft 31 in an amount dependent upon the speed of rotation of said shaft. As these weights move outwardly, they cam the thrust bearing device to the right (as the parts appear in Fig. 1) to exert pressure against the cylinder block 25, this pressure varying as a function of speed of rotation of the shaft and increasing as the speed of rotation of the shaft increases.

I prefer to arrange the parts so that the force exerted by the flyball governor will create a seal sufficient to balance the pressure desired to be

developed in the outlet recess 16 at a speed of rotation which is slightly below the operating speed of the pump. For example, in a pump developing 100 pounds per square inch pressure in the pressure chamber on the outlet side, the governor weights are so constructed and arranged that the force developed by the governor will create a seal sufficient to balance 100 pounds pressure in the recess 16 at a speed of 1700 R. P. M. of the drive shaft. During operation, the shaft rotates at 1800 R. P. M. Consequently, pumping pressure will not be developed until the pump reaches nearly top speed. When the drive shaft is stationary, the force exerted by the governor is zero, and there is no seal, so that the starting torque of the device will be at a minimum. The motor will, therefore, accelerate rapidly until a speed of 1700 R. P. M. is reached at which point the pump will be at effective operating condition and be developing 100 p. s. i. pressure, and at 1800 R. P. M. the pressure of the flyball governor device will create an effective seal between the recesses 16 and 20 to maintain this pressure with little or no loss. When the pump motor is shut off, the pressure on the outlet side will be dissipated when the speed drops below 1700 R. P. M., reducing the torque load so that the motor and pump are not rapidly braked, but may coast to a stop.

The provision of means for exerting variable pressure to force the end face of the block 25 against the end wall of the chamber 15 so that the pressure increases as the speed of movement of the block increases is considerably advantageous over means which provide a constant pressure, as for example a spring bearing against the block. With such a spring the pump must start against the torque provided by full pumping action.

I claim:

1. A pump comprising in combination, a casing having a cylindrical chamber therein, means providing an end wall in the chamber having an inner recess and a concentric outer annular recess, an annular rib forming part of said wall and located intermediate the recesses to separate the same, an inlet and an outlet port in the casing; passageways connecting said recesses respectively with the inlet and outlet ports; a cylindrical cylinder block of smaller diameter than said chamber nonrotatably mounted therein, a face at each end of the block with one end face engaging said end wall and with the other end face having a central well therein extending only partially through said block, a plurality of cylinders formed in the periphery of the block; a cylinder port for each cylinder and opening into said end face; a piston reciprocably mounted in each cylinder and having a portion extending therefrom and engaging the cylindrical wall of said chamber; a drive shaft mounted in said casing for rotation about an axis normal to the plane of the first mentioned end face; an eccentric projection on the end of said shaft and fitting movably in the well in said block for moving said block bodily in a generally circular path upon rotation of said shaft to reciprocate said pistons and to move said cylinder ports alternately into communication with said recesses; a flexible sleeve connecting said block and casing and surrounding said shaft to provide a nonrotatable seal between said cylinder ports and said shaft; and means for exerting variable pressure to force the first mentioned end face of said block against the end

wall of said chamber, comprising a spider on said shaft, a pair of oppositely disposed weights pivotally mounted on said spider and movable away from said spider as a function of the speed of rotation of said shaft, a thrust bearing between said weights and block, and a cam surface on each weight and engaging the bearing to increase said pressure as the speed of rotation of said shaft increases.

2. A pump comprising in combination, a casing having a cylindrical chamber therein, means providing an end wall in the chamber having an inner recess and a concentric outer annular recess, an annular rib forming part of said wall and located intermediate the recesses to separate the same, an inlet and an outlet in the casing; passageways connecting said recesses respectively with the inlet and outlet ports; a cylindrical cylinder block of smaller diameter than said chamber nonrotatably mounted therein, a face at each end of the block with one end face engaging said end wall and with the other end face having a central well therein extending only partially through said block, a plurality of cylinders formed in the periphery of the block; a cylinder port for each cylinder opening into said end face; a piston reciprocably mounted in each cylinder and having a portion extending therefrom and engaging the cylindrical wall of said chamber; a drive shaft mounted in said casing for rotation about an axis normal to the plane of the first mentioned end face; an eccentric projection on the end of said shaft and fitting movably in the well in said block for moving said block bodily in a generally circular path upon rotation of said shaft to reciprocate said pistons and to move said cylinder ports alternately into communication with said recesses; and means for exerting variable pressure to force the first mentioned end face of said block against the end wall of said chamber, said pressure increasing as the speed of rotation of said shaft increases.

3. A pump comprising in combination, a casing having a cylindrical chamber therein, means providing an end wall in the chamber having an inner recess and a concentric outer annular recess, an annular rib forming part of said wall and located intermediate the recesses to separate the same, an inlet and an outlet port in the casing; means connecting said recesses respectively with the inlet and outlet ports; a cylindrical cylinder block of smaller diameter than said chamber nonrotatably mounted therein, a face at each end of the block with one end face engaging said end wall and said block having a plurality of cylinders in its periphery each with a cylinder port opening into said end face; a piston reciprocably mounted in each cylinder and having a portion extending therefrom and engaging the cylindrical wall of said chamber; a drive shaft mounted in said casing for rotation about an axis normal to the plane of said end face; crank means movably coupling said shaft to the other end face of said block for moving said block bodily in a generally circular path upon rotation of said shaft to reciprocate said pistons and to move said cylinder ports alternately into communication with said recesses; a flexible sleeve connecting said block and casing and surrounding said shaft to provide a nonrotatable seal between said cylinder ports and said shaft; and means for exerting variable pressure to force the first mentioned end face of said block against the end wall of said chamber, said last named means comprising a flyball governor de-

vice on said shaft and a thrust bearing between said governor and said other end face of the block, a follower connected to the bearing and a cam surface on the governor engaging the follower to increase the pressure on said bearing as the speed of rotation of said shaft increases.

4. A pump comprising in combination, a casing having a cylindrical chamber therein, means defining an end wall in the chamber having inlet and outlet openings; a cylindrical cylinder block of smaller diameter than said chamber nonrotatably mounted therein, a face at each end of the block with one end face engaging said end wall, a cylinder in the block provided with a cylinder port opening into said end face; a piston reciprocably mounted in said cylinder and having a portion engageable with the cylindrical wall of said chamber; a drive shaft mounted in said casing for rotation about an axis normal to the plane of the first mentioned end face; crank means movably coupling said shaft to the other end face of said block for moving said block bodily in a generally circular path upon rotation of said shaft to reciprocate said piston and to move said port alternately into communication with said openings; and means for exerting variable pressure to force the first mentioned end face of said block against the end wall of said chamber, comprising a spider on said shaft, a pair of weights pivotally mounted on said spider and movable as a function of the speed of rotation of said shaft, and a thrust bearing between said weights and block, a cam surface on the weights and engaging the bearing to increase said pressure as the speed of rotation of said shaft increases.

5. A pump comprising in combination, a casing having a cylindrical chamber therein, means defining an end wall in the chamber having inlet and outlet openings; a cylindrical cylinder block of smaller diameter than said chamber nonrotatably mounted therein, a face at each end of the block with one end face engaging said end wall, a cylinder in the block provided with a cylinder port opening into said end face; a piston reciprocably mounted in said cylinder and having a portion engageable with the cylindrical wall of said chamber; a drive shaft mounted in said casing for rotation about an axis normal to the plane of the first mentioned end face; crank means movably coupling said shaft to the other end face of said block for moving said block bodily in a generally circular path upon rotation of said shaft to reciprocate said piston and to move said port alternately into communication with said openings; and means for exerting variable pressure to force the first mentioned end face of said block against the end wall of said chamber, comprising a flyball governor device on said shaft and a thrust bearing between said governor and said other end face of the block, and a cam surface operated by the governor to increase the pressure on said bearing as the speed of rotation of said shaft increases.

6. A pump comprising in combination, a casing having a cylindrical chamber therein, means defining an end wall in the chamber having inlet and outlet openings; a cylindrical cylinder block of smaller diameter than said chamber nonrotatably mounted therein, a face at each end of the block with one end face engaging said end wall, a cylinder in the block provided with a cylinder port opening into said end face; a piston reciprocably mounted in said cylinder and having a portion engageable with the cylindrical

wall of said chamber; a drive shaft mounted in said casing for rotation about an axis normal to the plane of the first mentioned end face; crank means movably coupling said shaft to the other end face of said block for moving said block bodily in a generally circular path upon rotation of said shaft to reciprocate said piston and to move said port alternately into communication with said openings; and means for exerting variable pressure to force the first mentioned end face of said block against the end wall of said chamber, said pressure increasing as the speed of rotation of said shaft increases.

7. A pump comprising in combination, a casing having a cylindrical chamber therein, means defining an end wall in the chamber having inlet and outlet openings; a cylindrical cylinder block of smaller diameter than said chamber nonrotatably mounted therein, a face at each end of the

5
10

block with one end face engaging said end wall, a cylinder in the block provided with a cylinder port opening into said end face; a piston reciprocably mounted in said cylinder and having a portion engageable with the cylindrical wall of said chamber; means for moving said block bodily in a generally circular path with said portion of the piston engaging the wall of the chamber to reciprocate the piston in the cylinder and to bring said port alternately in communication with the inlet and outlet; and means for exerting variable pressure to force the end face of said block against the end wall of said chamber, said pressure increasing as the speed of said movement increases.
